(57) **CLAIM**

The ornamental design for a handle for cookware, as shown and described.

DESCRIPTION

FIG. 1 is a perspective view of a handle for cookware, showing our new design.

FIG. 2 is a side view thereof;

FIG. 3 is a top view thereof;

FIG. 4 is a bottom view thereof;

FIG. 5 is a front view thereof; and,

FIG. 6 is a back view thereof.

The broken lines showing portions of the handle for cookware form no part of the claimed design.
